To all whom it may concern:

Be it known that I, Beatrice A. Shapiro, a citizen of the United States and a resident of Chicago, in the county of Cook and State of Illinois, have invented a new, original, and ornamental Design for a Perfume Bottle, of which the following is a specification, reference being had to the accompanying drawing, forming a part thereof, and in which:

Fig. 1 is a perspective view of a perfume bottle, showing my new design;

Fig. 2 is a top plan view of the same; and

Fig. 3 is a bottom plan view of the same.

I claim:

The ornamental design for a perfume bottle, as shown.

BEATRICE A. SHAPIRO.
